UNITED STATES PATENT OFFICE.

FRANK B. DONNELLAN, OF SAN FRANCISCO, CALIFORNIA.

MEANS FOR FEEDING CANS.

1,416,178.

Specification of Letters Patent. Patented May 16, 1922.

Application filed October 21, 1920. Serial No. 418,544.

To all whom it may concern:

Be it known that I, FRANK B. DONNELLAN, a citizen of the United States, and resident of San Francisco, county of San Francisco and State of California, have invented 5 a new and useful Improvement in Means for Feeding Cans, of which the following is a specification.

The present invention relates in general to 10 cooking retorts for canned food stuffs and has reference more particularly to means for introducing the cans into and withdrawing them from such retorts.

As heretofore practiced, canned food 15 stuffs are usually accommodated in retorts filled with high-pressure steam. In my co-pending applications, Serial Nos. 306,529 and 317,597, filed June 25 and August 14, 1920, respectively, I have disclosed a principle for 20 introducing the cans into the retort and withdrawing them therefrom without loss of steam. The present invention, while embodying practically the same fundamental principle as that disclosed in the two co-pending applications, is an improvement 25 thereon at least to the extent that the salient features of the present embodiment will offer a more practical solution of the problems involved.

30 In the accompanying drawings an illustrative embodiment of the invention is made to illustrate the application of the same. In said drawings Figure 1 is a side elevation of that form of cooking retort which has 35 been selected for the purpose of illustration and showing one form of the invention as applied thereto; Figure 2 is a detail view in cross-section of the retort, showing the revolving drums made to manipulate the cans 40 during the cooking operation; Figure 3 is a schematic view of the vacuum inducing means which is used in connection with the invention; Figure 4 is a side elevation partly in section of the introducing or withdraw- 45 ing means which, according to the present showing, is applied to diametrical opposite ends of the retort; Figure 5 is an end elevation of the same and Figures 6 and 7 are cross-sections on the line 6—7 Figure 4, and 50 showing the relative positions, one to the other, of the revolvable can receiving members.

Referring now to the drawings in detail, 55 the cooking retort (1) which has been selected for the purpose of illustration is of a

more or less conventional type and includes a relatively long cylindrical container of sufficient size to accommodate a quantity of cans at one time. The retort may be supported horizontally by the base members 60 (2) and (3) with steam connections (not shown) connecting the same with a suitable source of steam supply (also not shown). As is customary in these types of retorts, the interior is equipped with a multiplicity of 65 racks, each of which adapted to receive a single can, and all having a common rotatable mounting (4) which in turn is mounted upon an axial shaft (5) which extends through the retort, with means for driving 70 the same so that the cans may be passed from end to end of the retort.

Arranged upon the retort (1) at diametrical opposite ends thereof is the introducing and withdrawing means (6) and (7) 75 respectively, which will enable the cans to be introduced into and withdrawn from the retort while maintaining the desired steam pressure of the retort. The preferred construction of these means is best shown in 80 Figures 4 to 7 inclusive and attention is now directed to these Figures on sheet 2 of the drawings.

The retort will be equipped with two 85 openings, one for the introduction of the cans therein and one for the withdrawal; in other words, there will be an opening in the retort for the introducing means (6) and another opening for the withdrawing means (7). The part referred to by the nu- 90 meral (8) in Figure 4 will serve as an illustration in both instances. However, the position of the same in this Figure is such as to adapt it to the introducing means (6), but this is of no consequence, as the intro- 95 ducing means (6) and the withdrawing means (7) are of substantially the same construction—if not identical.

Briefly, the salient features of the introducing means (6) embody at least a pair of 100 can receiving compartments or the like (9) and (10) each of which is mounted parallel between an upper plate (11) and a lower plate (12) which plates are in turn confined between the plates (13) and (14) with a 105 shaft (15) passing through all of the plates parallel to the compartments (9) and (10) and fixed to the plates (11) and (12) but free to rotate in bearings in the plates (13) and (14). One end of this shaft is opera- 110

tively associated through means of a worm or other suitable drive consisting of the gears (16) and (17) with a shaft (18) which extends horizontally of the device and 5 terminates with a chain drive (19) on its end which is driven from the shaft (5).

As the compartments (9) and (10) are fixedly confined between the plates (11) and (12) and as the plates are fixedly connected to the shaft (15) and, further, as the plates (11) and (12) are mounted free to revolve between the plates (13) and (14), the shaft (5) becomes a driving element for revolving the compartments (9) and (10) 10 through means of the chain drive (19) and the worm or the like drive comprising the gears (16) and (17).

The plate (13) is provided with an opening (20) through its thickness and of a 20 diameter of that of the compartments (9) and (10). An opening (21) is also provided in the plate (14) cater-cornered from the opening (20) and of a diameter of that of the compartments (9) and (10) as well 25 as that of the opening (8) into the retort. The compartments (9) and (10) in being revolved between the plates (13) and (14) are adapted to register with the openings (20) and (21), the reason for which will be 30 fully appreciated as the description proceeds.

As a means of maintaining the plates (13) and (14) in place, as well as to offer the required frictional resistance to the 35 plates (11) and (12) which carry the compartments (9) and (10) and which have a ground fit between the first named plates, posts (22) are arranged to connect the plates (13) and (14) with a spring tension 40 device such as the coil springs or the like (23) provided for each post and adapted to impart a yielding clamping effect to draw the plates (13) and (14) together. These posts are of course arranged around the 45 circumference of the plates (11) and (12) so as not to interfere with their revolving movement.

Before proceeding further with the description of some of the details, it should be 50 noted that the drive imparted to the shaft (5) will, as above mentioned, revolve the compartments (9) and (10); therefore, considering the opening (20) in the plate (13) which registers with the top of the compartments as a can introducing opening into the device (6), as each of the compartments (9) and (10) register with the opening (20) a can may be introduced therein and carried around and deposited through the opening 55 (21) into the opening (8) of the retort, where it will be dropped or otherwise placed in a rack carried by the mounting (4). When one of the compartments (9) and (10) is in registering relation with the opening (20), the other compartment will be in

registering relation with (21) and the opening (8). In this connection, the compartment registering with the opening (21) and the opening (8) will be sealed by the plate (13), which will thus prevent the escape of 70 steam from the retort into the atmosphere. Naturally the compartment, however, will be filled with steam, which may be either returned into the retort through a suitable arrangement, or otherwise taken care of. 75 In so far as concerns the present embodiment, no attempt will be made to return the steam thus trapped in the compartment to the retort; nevertheless, the same will be treated or removed from the compartment 80 before the compartment reaches a registering position with the opening (20). To accomplish this, attention is directed to Figure 3 which shows a schematic arrangement. This figure, however, includes a joint connection for both the introducing device (6) and the withdrawing device (7); however, considering its use in connection with the introducing device (6), (9) and (10) represent the compartments shown in the other 85 figures as (9) and (10), and the position of the compartments in this figure is between the openings (20) and (21) or, in other words, both the top and bottom of the compartments when in this position are closed 90 by the plates (13) and (14).

Going back to Figure 4, or as better shown in dotted lines in Figure 6, ducts or communications (24) are arranged in opposite sides of the thickness of the plate (14) and 100 terminate in upwardly presented communications (25) which will establish a communication between the compartments and the ducts (24) when the compartments are revolved there-over. Connecting exteriorly 105 of the device and communicating with the ducts (24) is a tubing (26) and (27) (see Figure 7).

Again referring now to Figure 3, it will be seen that the tubing (26) and (27) connects with a manifold piping (28) which in turn has a branch connection (29) communicating with the suction or vacuum pump (30), which may be of any desirable construction. Connected to the vacuum pump 110 (30) by the piping (31) is a water condenser or the like (32). It will therefore follow that a suction created by the pump (30) is made in the tubing (26) and (27) and when the compartments are in registering relation therewith, the steam contained 115 in one compartment and the air contained in the other compartment will be sucked therefrom and introduced into the condenser (32) where the steam will be condensed and where the air may be discharged 120 into the atmosphere through the opening (33). Therefore it will now follow that the steam admitted to the compartment communicating with the retort will be with- 125 130

drawn before the compartment reaches a registering position with the opening (20) and at the same time the air contained in the compartment which has just been moved 5 away from the opening (20) with the can therein, will be withdrawn before it reaches a registering position with the opening in the retort for releasing the can.

When the can is introduced into the compartment and as the length of the compartments includes the thickness of the plate (12) it is desirable to prevent the can from 10 resting upon the plate (14), as the friction thus created would retard and interfere with the effective operation of the device; therefore, each one of the compartments is provided with a movable supporting ledge or shelf (34) which is arranged in the compartments radially thereof and embodying 15 in its construction a stem (35) which passes through the stuffing box or packing gland (36) and terminates exteriorly of the compartments as well as on the edge of the plate (12). Fixed on the end of the stem is 20 a lug or the like (37) which is seated in an annular groove (38) as best shown in Figures 6 and 7. As the compartments revolve, the lugs (37) will travel around in the groove (38) and in order that the shelves 25 (34) may be receded so as not to interfere with the discharge or release of the can from the compartment into the retort, the inner edge of the groove (38) is produced with a lip (39) at a point opposite the opening into 30 the retort so that the lugs may ride over the lip and recede the shelves (34) to inactive position confined in a pocket made for this purpose in the lower part of the compartments.

With this arrangement it is possible to support the cans in the compartments above the plate (14) until they are moved into position to be released into the retort, whereupon the shelves (34) will be manipulated 45 as described.

The description so far has been directed primarily to the construction and operation of the can introducing device (6), but in so far as concerns the withdrawing means (7) 50 the construction may be identical, as the same function is realized in both the introduction and the withdrawal of the cans. To accommodate the device to the withdrawal of the cans, it need be only reversed in position, with the same driving means such as the chain drive (19) and the same revolving means such as the worm drive (16) and (17).

When the can has been dropped from the 60 retort into the receiving one of the compartments (9) and (10) in the withdrawal device, the steam admitted into the compartment will be displaced by the can and forced back into the retort; therefore no special attention need be paid to the removal of steam 65

in this instance; at the same time it is thought best to connect the withdrawing device with the suction creating pump (30) in the same way that the introducing device (6) is connected, to which end the manifold 70 piping (28) will have branch pipes or tubings (26^a) and (27^a) communicating therewith and with the same connected to the withdrawing device in exactly the same manner as the tubings (26) and (27) are 75 connected to the introducing device. It is to be noted that when the compartments (9) and (10) of the introducing means are communicating with the tubings (26) and (27) the compartments of the withdrawing means 80 are just in opposite position.

It will be readily appreciated that while that form of the invention selected for the purpose of illustration is shown in combination with a horizontal retort, the principle involved may be used in connection with a vertical retort; or in fact both the can introducing and withdrawing devices may be arranged on the ends of the retort even when the same is in a horizontal position; 90 however, in this form some suitable pusher or the like should be applied to deposit the cans within the retort and for ejecting them therefrom at the opposite end.

I claim:

1. In a cooking retort, a can feeding device comprising an opening in the retort, a plurality of cylinders revolvably mounted over the retort so as to successively register with the opening, a plate supported above 100 the cylinders, means for holding the same in yielding contact with the cylinders, and a can inlet in said plate not registering with the opening in the retort but adapted to successively register with the cylinders. 105

2. In a cooking retort, a can feeding device comprising an opening in the retort, a plate supported in spaced relation to the opening having a can inlet not registering with the opening, a cylinder revolvably 110 mounted between the retort and the plate adapted to successively register with the can inlet to receive a can and with the opening to discharge the can into retort, and vacuum means for withdrawing steam from the cylinder while the same is travelling between the opening and the can inlet. 115

3. In a cooking retort, a can feeding device comprising an opening in the retort, a plate supported in spaced relation to the 120 opening having a can inlet not registering with the opening, and a cylinder revolvably mounted between the retort and the plate adapted to successively register with the can inlet to receive a can and with the opening 125 to discharge the can into the retort, and means associated with the cylinders for supporting the cans while in transit.

4. In a cooking retort, a can feeding device comprising an opening in the retort, a 130

plate supported in spaced relation to the opening having a can inlet not registering with the opening, a cylinder revolvably mounted between the retort and the plate adapted to successively register with the can inlet to receive a can and with the opening to discharge the can into the retort, and

means associated with the cylinders for supporting the cans while in transit, said means comprising a shelf extending into each cylinder and means for withdrawing the same when the cylinder registers with the retort opening.

FRANK B. DONNELLAN.
